United States Patent Office

Des. 179,148
Patented Nov. 6, 1956

179,148

TOY TARGET

Clair Omar Musser, Studio City, Calif., assignor to
Knickerbocker Plastic Company, Inc., North Holly-
wood, Calif., a corporation of California

Application October 20, 1955, Serial No. 38,496

Term of patent 14 years

(Cl. D34—5)

The figure shows a perspective view of a toy target embodying my new design.

The rear portions of the device of applicant's design are substantially plain and unornamental.

I claim:

The ornamental design for a toy target, substantially as shown and described.
